ington, N. J., a corporation of New Jersey

Application April 7, 1943, Serial No. 482,118
In Great Britain April 24, 1942

8 Claims. (Cl. 33—147)

This invention relates to grading machines, such machines having operating mechanism adapted to act upon or with respect to work-pieces in accordance with their measured thicknesses; and is herein illustrated as an improvement upon the machine of Letters Patent of the United States No. 2,338,283, granted January 4, 1944, upon an application filed in the names of Joseph Gouldbourn and Charles H. Heather.

The machine of the patent comprises measuring mechanism, operating mechanism and mechanism including fluid-operated means for adjusting the operating mechanism in accordance with the thickness of the thinnest spot in a selected locality of the workpiece encountered by the measuring mechanism as the workpiece passes through the machine. In that machine, in which two pawls cooperate with rack teeth on a setting slide to lock the slide from movement in either direction, an undue amount of wear or breakage is liable to occur due to the fact that, when that pawl, which is preventing return movement of the slide to its zero position, is withdrawn from the ratchet teeth, the hydraulic or fluid-operated pressure is pushing the slide toward its zero position in a direction to hold a tooth of the ratchet against the pawl.

According to one feature of the present invention, means is provided for reversing the direction in which the hydraulic pressure is exerted just as or prior to the withdrawal of the pawl from the ratchet teeth of the setting slide.

According to another feature of the invention, means is provided for causing the machine to deal in a certain manner with each workpiece, the thickness of the thinnest measured spot of which is not an even multiple of the chosen unit of measurement. According to this feature, a workpiece, the thinnest spot in the measured portion of which does not measure an even multiple of the chosen unit of measurement, will be dealt with as though its thickness were the nearest multiple of a unit, whether said thickness is a little above or a little below the nearest multiple; and, in the case of a workpiece the thinnest spot of which is exactly a multiple of the unit plus half a unit, said workpiece will be dealt with as though the thickness of its thinnest spot were the next higher multiple of the unit.

These and other features of the invention, including certain details of construction and combinations of parts, will be described as embodied in an illustrative machine and pointed out in the appended claims.

Referring to the accompanying drawings, Fig. 1 is a plan view of the illustrative machine;

Figs. 2 and 3 taken together are a vertical section on the line II, III of Fig. 1, Fig. 2 showing the upper portion and Fig. 3 the lower portion of the machine;

Fig. 4 is a side elevation of the mechanism for moving the pawls into and out of cooperative relation to the setting slide; and

Figs. 5, 6 and 7 are diagrammatic views showing the operation of the pawls on the setting slide.

The illustrative machine, as has been stated, 15 is an improvement upon the machine of Patent No. 2,338,283, certain parts of which are shown in detail in Patent No. 1,703,955 granted March 5, 1929 upon an application filed in the name of William T. B. Roberts; and, before describing 20 the improved mechanism, a brief description of what is old will be given.

The machine comprises measuring mechanism including cooperating rolls 1, 3 (Fig. 2) at the front of the machine, operating mechanism at 25 the rear of the machine and fluid-operated mechanism, indicated as a whole at 4 for adjusting the operating mechanism in accordance with the thinnest spot in a selected locality of the workpiece encountered by the measuring rolls. Machines of this general type are known which split and mark the workpieces and which sort them or visually indicate their thicknesses. The operating mechanism of the illustrated machine consists of a splitting mechanism, of which the 30 rolls are indicated at 5 (Fig. 2) and 7 (Fig. 3), a knife 8, and a marking mechanism, of which the stamping or marking wheel is indicated at 147 (Fig. 2). These two operating mechanisms are typical of any mechanism which acts upon 35 or with respect to the workpiece in accordance with its thickness as measured by the measuring mechanism.

The measuring mechanism includes the driven 40 measuring rolls 1, 3, the roll 1 being prevented from upward or downward movement and the roll 3 being yieldingly supported and being capable of moving bodily downward and of tipping lengthwise as a workpiece passes between the rolls. The lower roll 7 of the splitting mechanism 45 is yieldingly supported, the upper roll being adjustable in accordance with the thinnest spot of each workpiece measured by the measuring mechanism. The fluid-operated adjusting mechanism is controlled by the lower measuring roll 3 and causes a setting slide 9 to be 50 55

moved laterally of the machine. The setting slide is moved laterally of the machine by the movement of the stem 11 of a piston, endwise movement of which is controlled by valve mechanism similar to that shown in detail in Patent No. 2,338,283. The stem 11 (Fig. 3) has formed on it rack teeth which mesh with a pinion 13 on the lower end of a shaft 15 which has received on its upper end a gear 17 (Fig. 1), said gear meshing with rack teeth 19 on the setting slide 9.

As a workpiece passes between the measuring rolls 1, 3, the lower roll 3 may move up or down as the thickness of the workpiece varies; and the movement of the roll so controls the valve mechanism that the stem 11 of the piston moves the setting slide 9 laterally of the machine. When the measuring of the workpiece ceases, the setting slide is locked against movement in both directions laterally of the machine; and, while the setting slide remains so locked, the upper roll of the splitting mechanism is adjusted vertically in accordance with the position of the setting slide, that is, in accordance with the thickness of the thinnest portion of the workpiece measured by the measuring mechanism. The stamping wheel 147 is adjusted angularly by the movements of the setting slide.

The mechanism for adjusting the vertical position of the upper roll 5 of the splitting mechanism is similar to that disclosed in Patent No. 1,703,955 and comprises a slide 21 (Fig. 1) similar to the slide 108 of the last-named patent and a wedge member having on it an inclined face 23 which is arranged to engage an inclined face 25 on the setting slide 9 when the slide 21 is moved forward. The slide 21 has on it rack teeth 27 which mesh with a pinion 29 which also meshes with rack teeth 31 on one end of a rack bar 33 similar to the rack bar 82 of the last-named patent. The rack bar 33 has on its opposite end rack teeth 35 which mesh with a pinion 37. The pinions 29, 37 are secured on vertical spindles which are rotatably mounted in the machine frame and have on them rotatable members 39 on which are formed spirally inclined faces similar to the faces 73, 75 of the last-named patent. Bearings for the upper splitting roll 5 have on them blocks, similar to the blocks referred to as spiralled blocks 76, 77 in the last-named patent, on which are formed complementary spiralled faces.

After the setting slide 9 has been locked in position laterally of the machine the slide 21 is moved forwardly until the face 23 engages the face 25 on the setting slide 9. During this forward movement of the slide 21 the members 39 are rotated, and the spirally inclined faces on the members are rotated relatively to the aforesaid complementary spirally inclined faces on the blocks on the bearings of the upper splitting roll 5. The spirally inclined faces on the blocks 39 determine the position heightwise of the upper splitting roll 5 when the workpiece is being fed by the splitting rolls to a splitting knife 8 secured in the machine frame. The slide 21, which is moved forwardly by mechanism similar to that described in the last-named patent, comprises a rod 41 (Fig. 2), similar to the rod 99 of the last-named patent, which is connected to a cam-operated arm 43, similar to the arm 97 of the last-named patent, and devices connecting the slide to the wedge member. When the blocks 39 have been rotated by the forward movement of the slide 21, they are locked in this

position by a ratchet and pawl similar to the circular ratchet 84 and pawl 85 of the last-named patent. No further description of the old machine will be given, reference being made to the two Patents No. 1,703,955 and No. 2,338,283 for details of construction not herein described.

In the illustrative machine of the present invention the setting slide 9, instead of having on it two rows of oppositely disposed ratchet teeth, such as the teeth referred to as the teeth 40, 41 in Patent No. 1,703,955, has on it only one row of ratchet teeth 45 (Fig. 1), which are spaced apart half an iron, i. e., the distance the setting slide 9 is moved if a workpiece increases or decreases half an iron in thickness. Cooperating with the teeth 45 is a pawl device, which comprises a pair of pawls 47, 49. The ratchet teeth 45 and pawl device are so arranged as to prevent movement of the setting slide, during the measuring of a workpiece in the direction of the arrow in Fig. 1, in response to increases in the thickness of the workpiece but to allow movement of the setting slide in the opposite direction in response to decreases in the thickness of the workpiece.

When, in the machine described in the Patent No. 2,338,283, the measuring of a workpiece ceases, the hydraulic pressure is usually tending to move the setting slide towards its starting or zero position. In the illustrative machine hydraulic pressure, which is tending to move the setting slide 9 towards its zero position during the measuring of a workpiece, is reversed by the fall of the gate 113 as it rides off from the trailing end of a workpiece just as the measuring of the workpiece ceases; and the hydraulic pressure holds the tooth then in engagement with the pawl device firmly against the pawl device. The setting slide 9 is thus held against movement in either direction across the machine by the hydraulic pressure and the pawl device, while the operating mechanism is adjusted in accordance with the position of the setting slide 9 across the machine. After the operating mechanism has been adjusted and locked in adjusted position the hydraulic pressure is again reversed by the raising of the gate 113 to cause the setting slide 9 to return to its zero position. The pawl device is withdrawn from the ratchet teeth 45 as or just after the hydraulic pressure is reversed to return the setting slide 9 to zero position so that there is no pressure on the teeth of the pawl device and ratchet teeth as the pawl device is withdrawn.

The pawl device comprises the aforesaid two pawls 47 and 49 each having formed thereon teeth which are arranged to engage the single row of ratchet teeth 45. When the teeth on the pawl 47 and teeth 45 are pressed together lengthwise of the row of teeth 45, the teeth on the pawl 49 engage the teeth 45 about half way along adjacent teeth for a purpose hereinafter described. The ratchet teeth 45 are so spaced apart that movement of the setting slide 9 across the machine a distance equal to the distance between two adjacent teeth represents an increase or decrease of half an iron in the thickness of a workpiece being measured, an iron being one forty-eighth of an inch. The pawl 47 is pivotally mounted at 51 on the machine frame and is arranged to be moved into engagement with the ratchet teeth 45 by a spring plunger 53. The pawl 49 is pivoted at 55 to a cam lever 57 and is arranged to be moved into engagement with the ratchet teeth 45 by a spring 59 connected to the

pawl 49 and cam lever 57. When the cam lever 57 is swung inwardly, as will presently be described, the pawl 49 is moved in a direction to push the setting slide 9 a short distance (less than one tooth) against the hydraulic pressure and in a direction opposite to that indicated by the arrow in Fig. 1.

The pawls 47, 49 are both allowed to be moved by the spring plunger 53 and spring 59 into engagement with the ratchet teeth 45 and are both moved away therefrom by a block 61 secured on the rear end portion of a horizontal rod 63 extending forwardly and rearwardly of the machine and being connected to a bar 65 slidingly mounted in the machine frame. Referring more particularly to Fig. 4, the upper face of the bar 65 has formed in it a recess 67 which is arranged to be engaged by an actuating pawl 69 which is pivoted on an actuating slide 71, arranged to be moved forwardly and rearwardly of the machine parallel to the bar 65. The actuating slide 71 is moved rearwardly by a spring 73, which is stronger than the spring of the spring plunger 53 and spring 59 which respectively actuate the pawls 47, 49, and the tension spring 66, said last-named spring being fastened at one end to the bar 65 and at the other end to a stationary part of the machine. The rearward movement of the actuating slide 71 is limited by a stop face 75 on the machine frame. The spring 73, through the actuating slide 71, actuating pawl 69 and bar 65, causes the pawls 47, 49 to be moved and held out of engagement with the ratchet teeth 45 on the setting slide 9. The actuating slide 71 has formed in it a horizontal slot 77 which is engaged by a stud 79 secured in a substantially horizontal link 81 which extends rearwardly from the stud and is pivoted at its rear end to a cam lever 83 (Fig. 2), corresponding to the cam lever referred to as the cam lever 30 in Patent No. 1,703,955. The actuating pawl 69 is arranged to be raised out of engagement with the recess 67 in the bar 65, to allow the pawls 47, 49 to be moved into engagement with the ratchet teeth 45 on the setting slide 9, by an upwardly and downwardly extending thrust rod 85 which has formed on it a shoulder 87 arranged to engage a pin in the actuating pawl 69 and to raise it out of the recess 67 in the bar 65 against the action of a tension spring 89 which tends to move the actuating pawl into engagement with the bar. The lower end portion of the thrust rod 85 is pivotally connected to a substantially horizontal arm 91 (Fig. 2) which is arranged to be swung upwardly when a shoe 93, corresponding to the shoe 50 of the last-named patent, is moved upwardly by a workpiece which is passing between the measuring rolls 1 and 3 and is being fed towards the splitting rolls by a chain 95 against which the workpiece is held by a pressure device having freely rotatable rolls 97 which engage the workpiece. When, therefore, a workpiece passes beneath and raises the shoe 93, the pawls 47, 49 are allowed to be moved into engagement with the ratchet teeth 45 on the setting slide 9, and the bar 65 is moved forwardly by the spring 66 (Fig. 4). Forward movement of the bar 65 is limited by the engagement of a block 99 on the bar with a plate 101 on the frame but is sufficient to allow the pawls 47, 49 to fully engage the ratchet teeth 45. When the bar 65 moves forwardly the recess 67 in the bar, out of which the actuating pawl 69 has been moved, is moved forwardly of the pawl.

As a workpiece is being fed rearwardly of the machine, its leading end portion engages a plate

103 (Fig. 2) near the splitting rolls 5, 7 similar to the plate 11 of the last-named patent and raises the plate which, through arms 105, 107 and trip rod 109, corresponding respectively to the arms and trip rod 17, 20 and 22 of said patent, causes a clutch to be closed and a driving shaft 111 to be rotated. As the driving shaft 111 rotates, the actuating slide 71 is moved first forwardly by the link 81 and then rearwardly by the spring 73. As the actuating slide moves forwardly, the actuating pawl 69 is moved with it and is carried in front of the recess 67 in the bar 65 and away from the thrust rod 85 so that the actuating pawl 69 is moved by the aforesaid tension spring 89, which is connected to the pawl 69 and to the thrust rod 85, from the shoulder 87 on the thrust rod 85 down upon the upper face of the bar 65. As the actuating slide 71 is moved rearwardly by its spring 73, allowed by rearward movement of the pin 79 in the actuating link 81, the actuating pawl 69 engages the recess 67 in the bar 65 and moves the latter bar rearwardly and the pawls 47, 49 out of engagement with the ratchet teeth 45 on the setting slide 9.

25 When a gate 113 (Fig. 2) corresponding to the gate 84 of Patent No. 2,338,283 drops off the trailing end of a workpiece, a lever 115 connected to the gate 113 so controls the auxiliary valve, described in said patent that the ratchet teeth on the setting slide 9 which are in engagement with the teeth on the pawl 47 are pressed firmly against the teeth on the pawl and endwise movement of the setting slide 9 is thus prevented while the operating means for dealing with the workpiece is being adjusted. The hydraulic pressure is, thus tending to move the setting slide in the direction in which it is moved when a workpiece enters between the measuring rolls, that is, in the direction in which it would move, if allowed, in response to increases in thickness of a workpiece which is passing between the measuring rolls. This control of the auxiliary valve is so arranged that it is effective when the gate drops off the thinnest work with which the machine is capable of dealing.

40 The lever 115 is pivoted at 117 on a bracket 119 secured to a valve bracket 121, similar to the bracket referred to as the valve bracket 187 in Patent No. 2,338,283. The lever 115 is pivotally connected to the lower end portion of a rod 123. The upper end portion of the rod 123 has secured in it a pin 125 which engages a slot 127 formed in an arm 129 extending from a shaft 131 to which the gate 113 is secured. As the gate 113 drops off the trailing end of a workpiece, a member 133 adjustably secured on the arm 129 engages the pin 125 and raises the rod 123. Upward movement of the rod 123 swings the lever 115 about its pivot and causes the lever to engage a pin 135 in a valve lever 137, similar to the lever referred to as the valve lever 163 of the last-named patent, which controls the aforesaid auxiliary valve, and to move the valve lever 137 forwardly so as to cause the hydraulic pressure to press the aforesaid teeth on the setting slide against the teeth on the pawl 47. The gate is raised by mechanism similar to that described in Patent No. 1,703,955 and comprising a cam-operated bar 139, similar to the bar 66 of said patent which is controlled by movement of the lower measuring roll 3; and, when the gate is raised, the lever 115 is moved away from the pin 135, and the auxiliary valve is actuated so as to cause the hydraulic pressure to be reversed and the setting slide 9 to be moved to its zero posi-

tion. This reversal of the hydraulic pressure is arranged to occur just as or before the pawls 47, 49 are moved out of engagement with the ratchet teeth 45 on the setting slide 9 so that the pawls and teeth are not pressed together when the pawls are withdrawn and wear of the teeth or pawls is at least substantially avoided. In the operation of the machine workpieces are fed to it in quick succession, the machine being ready to receive the leading end of a succeeding workpiece while a preceding workpiece is being split, so that ordinarily there are two workpieces in the machine all the time. Assuming, however, that no workpiece is in the machine, that the gate is in raised position and consequently that the hydraulic pressure device has moved the setting slide 9 to zero position, and that the pawl device has been moved out of engagement with the rack teeth on the setting slide, the operation of the machine is as follows.

A workpiece is presented to the machine, and as soon as the leading end of said piece enters between the measuring rolls 1, 3 the gate 113 is tripped and descends upon the workpiece as is usual in this type of machine. The gate rides upon the upper surface of the workpiece until it rides off from the trailing end of said piece and falls. It is this falling of the gate which, through the rod 123 (Fig. 3), causes the hydraulic mechanism, indicated as a whole at 4, to act through the piston rod 11 and the parts which connect it to the setting slide 9 to press the slide endwise against the teeth of the pawl device so that the slide is held immovable during the time that the upper roll of the splitting mechanism is adjusted. The operation of the two pawls 47, 49 on workpieces having thinnest spots of a thickness which does not correspond to the half-iron spacing of the teeth 45 will be described later. At present it will be assumed that the thinnest spot in a workpiece corresponds to the half-iron spacing of the teeth 45 and that the pawl 47 is alone effective.

Returning now to the position of parts when the gate descends upon the upper face of the workpiece and the gate is riding upon said upper face, the lower roll 3 of the measuring mechanism moves up and down in response to variations in the thickness of the workpiece and, through the hydraulic mechanism, causes the setting slide 9 to move back and forth crosswise of the machine. Thereafter, until the leading end of the workpiece enters beneath and lifts the shoe 93 (Fig. 2), no effective measuring takes place since the setting slide 9 is free to move back and forth according to increase or decrease in the thickness of the workpiece. When now the leading end of the workpiece raises the shoe 93, the link 85 is pushed up to allow the spring 66 (Fig. 4) to pull the bar 65 and rod 63 forward so as to permit the pawl device (Fig. 1) to be moved into engagement with the rack teeth 45 on the setting slide 9. As long as the pawl device remains in engagement with the rack teeth, the effective measuring of the workpiece continues, the setting slide moving only toward zero position so that only increments of thinness, so to speak, are effective.

The movements of the setting slide in response to thinner spots encountered in the workpiece by the measuring rolls continues until the gate 113 rides off the trailing end of the workpiece and falls. This falling of the gate, through the rod 123 (Fig. 3), causes the hydraulic mechanism to exert a pressure on the setting slide 9 in the

direction indicated by the arrow in Fig. 1 so that the setting slide is held from movement for a short interval. During this interval four things take place before the leading end of the workpiece has entered between the open rolls of the splitting mechanism, due to the fact that the raising of the plate 103 through a suitable clutch (not shown) causes rotation of the shaft 111. First, a pawl, corresponding to the pawl 85 of Patent No. 1,703,955, is withdrawn from a circular ratchet, corresponding to the circular ratchet 85 of the last-named patent. Second, the pawl device is thrown into operation. Third, the upper roll 5 is adjusted downwardly by pulling forward the slide 21 which corresponds to the slide 108 shown in Fig. 4 of the last-named patent, the pulling forward of this slide being accomplished by mechanism corresponding to that shown in Fig. 4 of the last-named patent, namely, by the rod 41, corresponding to the rod 99 of the last-named patent, and cam-operated arm 43 corresponding to the arm 97 of the last-named patent. Fourth, the pawl which corresponds to the pawl 85 of the last-named patent is allowed again to engage the circular ratchet corresponding to the circular ratchet of the last-named patent. The splitting mechanism has now been set in accordance with the measured thickness of the workpiece and locked in position. The gate 113 is thereafter raised by the cam-operated bar 139 corresponding to the bar 66 shown in Fig. 1 of the last-named patent. This reverses the direction of the hydraulic pressure so that said pressure is exerted to move the setting slide 9 toward zero position, that is, in a direction opposite to that indicated by the arrow in Fig. 1, thereby releasing the pressure of the rack teeth 45 on the pawl device, and, just as the pressure on the pawl device is relieved, the link 81 (Fig. 2) is moved by the cam lever 83 with the result that, through the mechanism shown in Fig. 4, the pawl device is moved out of engagement with the rack teeth on the setting slide.

5 The gate has now been raised and the pawl device disengaged from the rack teeth on the setting slide so that a succeeding workpiece may be fed at once to the machine. During the time, 10 or part of the time, that said succeeding piece is being measured, the preceding piece is being split; and the upper roll of the splitting mechanism is being held down in its adjusted position, being held locked by mechanism shown in Patent 1,703,955, namely by the pawl 85 (of the last-named patent) which engages the circular ratchet 84 (of the last-named patent). When the leading end of the succeeding workpiece raises the plate 103 (of the present application) and starts rotation of the shaft 111 (of the present application), the first thing which rotation of this shaft accomplishes is to withdraw the pawl 85 (of the last-named patent) from the teeth of the circular ratchet 84 (of the last-named patent) and thereby permit the upper roll 15 of the splitting mechanism to rise to its normal position ready to be adjusted again. It will be realized that the raising of the gate 113 to allow another workpiece to be fed to the machine, and therefore the reversal of the hydraulic pressure, and the withdrawal of the pawls 47, 49 from the ratchet teeth 45 on the setting slide 9 are both controlled by cam-operated means while the driving shaft is being rotated and may therefore be so accurately timed that the pressure

between the pawls and ratchet teeth is definitely relieved at the time when the pawls are withdrawn from the teeth. The only function of the shoe 93 in the illustrative machine is to release the actuating pawl 69 from the recess 67 in the bar 65, as a workpiece raises the shoe, to allow the pawls 47, 49 to be moved into engagement with the ratchet teeth 45 on the setting slide 9 and measuring of the workpiece to be commenced. The locking means referred to in Patent No. 2,338,283 for preventing forward movement of the arm referred to as the downwardly extending arm 149 is dispensed with in the illustrative machine.

The pawl 47, as has been stated, is pivoted on the machine frame and has three teeth; and, when three teeth on the setting slide 9 are pressed by the hydraulic pressure against the teeth on this pawl, the setting slide 9 will be so positioned that the means for operating upon or dealing with the workpiece just measured will be adjusted accurately to a whole iron or half iron dimension depending upon the thickness of the workpiece and not to a dimension between an iron and half an iron. To this end the pawl 49, as has been stated, is pivoted on the cam-operated lever 57 which is pivoted on the machine frame and has on it a cam roll 141 which is held by a tension spring 143 against a cam block 145 on an arm corresponding to the arm 97 of Patent No. 1,703,955. The pawls 47, 49 each have three teeth arranged to engage the ratchet teeth 45 on the setting slide 9. When the teeth 45 are pressed, lengthwise of the slide, against three of the teeth on the pawl 47, the teeth on the pawl 49 engage halfway along three other teeth of the teeth 45; and the teeth on the pawl 49 are arranged to be moved lengthwise of the setting slide 9 into alignment with the teeth on the pawl 47 by the cam lever 57.

The marking or stamping mechanism comprises the stamp wheel 147 carrying a series of stamps which are arranged to stamp workpieces with numerals according to their measured thickness in whole irons or half irons and a manually adjustable size wheel 149. The stamp wheel 147 is connected to the setting slide 9, as is usual in machines of this type, and is adjusted by movement of the setting slide across the machine, the stamp wheel being locked by the locking of the setting slide in its adjusted position during its stamping movement. The stamping mechanism is similar to that disclosed in Patent No. 1,571,967, granted February 9, 1926 upon an application filed in the names of William T. B. Roberts and Fred Ricks, the details of its construction forming no part of the present invention.

It is desirable that a workpiece which measures between, say, four and four and a half irons shall be dealt with as a four or four and a half iron workpiece whichever is nearest to its measured thickness. To this end the pawl device is constructed and arranged to ensure that the stamping and splitting mechanism shall be properly positioned for each operation, and that each workpiece which measures between, say, three and three and a half irons shall be dealt with as if it measured three or three and a half irons whichever is nearest to its measured thickness. The aforesaid cam lever 57 to which the pawl 49 is pivoted is arranged to actuate the pawl 49 just after the hydraulic pressure has been caused to press three teeth on the setting slide, lengthwise of the slide, against the teeth on the pawl 47

which is pivoted on the machine frame. When the hydraulic pressure causes three teeth on the setting slide to be pressed against the teeth on the pawl 47 both pawls of the device are in engagement with the ratchet teeth 45 on the setting slide, the teeth of the cam actuated pawl 49 being spaced about half-way along three of the teeth on the setting slide. The operation of the pawls 47, 49, when different thicknesses of work have been measured by the measuring mechanism and the setting slide has in consequence been moved to different positions across the machine, will now be described with reference to Figs. 4, 5 and 6 in which the teeth 45 have been shown to a relatively large scale and the pawls have been shown with only one tooth each instead of three.

When, for example, and as shown in Fig. 5, the gate 113 drops off a workpiece which has been found by the measuring mechanism to measure four irons and the hydraulic pressure is reversed so that it is tending to move the setting slide 9 in the direction in which it moves, if allowed, in response to an increase in thickness of the work (up as viewed in the figure), a tooth 151 of the ratchet teeth 45 on the setting slide 9 corresponding to the four iron measurement is pressed against the pawl 47; and the pawl 49 engages the next tooth 153, which corresponds to a three and a half iron measurement, about half way along that tooth. When thereafter the pawl 49 is actuated by its cam lever 57 it, in this instance, moves idly towards and from the four iron tooth 151, and the workpiece is dealt with in accordance with its four iron measurement.

If a workpiece measures slightly less than four and a quarter irons (see Fig. 6) the pawl 49 will be in a position to be engaged by the four iron tooth 151 when the hydraulic pressure is reversed, and the pawl 47 will be engaging the four iron tooth 151 between that tooth and the next or four and a half iron tooth 155; and the four iron tooth will be pressed against the pawl 49 by the hydraulic pressure. When thereafter the pawl 49 is actuated by its cam lever 57 it pushes the setting slide 9 against the hydraulic pressure so far that the pawl 47 can drop in behind the four iron tooth 151 and then, as the pawl 49 is moved back, the hydraulic pressure pushes the four iron tooth 151 against the pawl 47. The workpiece although it has been found to measure just under four and a quarter irons is thereafter dealt with as if it measured four irons.

If a workpiece is found to measure just over three and three-quarter irons (see Fig. 7) both pawls will be engaging the three and a half-iron tooth 153, the pawl 49 being close to the top of the tooth and the pawl 47 being about half way along the tooth. When the hydraulic pressure is reversed, the four-iron tooth 151 will be pressed against the pawl 47 and when the pawl 49 is actuated by its cam lever 57 it is moved idly toward and from the four-iron tooth. The workpiece is thereafter dealt with as if it were found to measure four irons.

It will therefore be apparent that workpieces which measure between just over three and three-quarters of an iron and just under four and a quarter irons are all dealt with as if they measured four irons. If, however, a workpiece measures exactly four and a quarter irons the pawl 49 will be in engagement with the top of the four-iron tooth, and, when the hydraulic pressure is reversed, the four and a half iron-tooth will be pressed against the pawl 47, and the cam-oper-

ated movement of the pawl 49 will be an idle movement and the workpiece will be dealt with as if it measured four and a half irons. Although in the above example a thickness of four irons as a base is described and measurements above and below four irons have been referred to, it is to be understood that this is only by way of example, the same results occurring with other base measurements. By this means any workpiece in which its thinnest measured portion does not measure an iron or half-iron dimension is dealt with in accordance with its nearest iron or half-iron measurement whether it is a little below or a little above that measurement except as above indicated where a workpiece measures exactly four and a quarter irons when it is dealt with as if it measured four and a half irons.

Having thus described the invention, what I claim as new and desire to secure by Letters Patent of the United States is:

1. A combination measuring mechanism responsive to variations in the thickness of a workpiece passing through the machine, operating mechanism, mechanism for adjusting the operating mechanism in accordance with the thickness of a thin spot encountered by the measuring mechanism, said adjusting mechanism including a setting member having rack teeth, a pawl for cooperating with said teeth and hydraulic means for moving the setting member, the pawl permitting movement in a direction corresponding to thinner spots encountered by the measuring mechanism, means becoming operative after the completion of the measuring operation for reversing the direction of the hydraulic pressure to hold the setting member locked from movement in either direction, means for withdrawing the pawl, and means acting just prior to said withdrawal for again reversing the direction of the hydraulic pressure to permit ready withdrawal of said pawl.

2. In a machine for measuring the thickness of the thinnest spot in a selected locality of a workpiece and for operating in accordance with said thickness, a setting member, hydraulic means for adjusting the setting member, a pawl adapted to cooperate with the setting member to permit movement of the setting member in one direction but not in the other, means becoming operative at the end of the measuring operation for causing the hydraulic pressure to be exerted in a direction opposite to the direction of movement of the setting member permitted by the pawl whereby the setting member is held immovable for an interval, means for reversing the direction of the hydraulic pressure, and means for withdrawing the pawl.

3. In a machine for measuring the thickness of the thinnest spot in a selected locality of a workpiece and for operating in accordance with said thickness, a setting member, means for adjusting the setting member, a pawl adapted to cooperate with the setting member to permit movement of the setting member in one direction but not in the other, means becoming operative at the end of the measuring operation for causing the means for adjusting the setting member to tend to move the member in a direction opposite to the direction of movement of said setting member permitted by the pawl whereby the setting member is held immovable for an interval, means for thereafter causing the means for adjusting the setting member to tend to move the member in a direction permitted by the pawl, and means for withdrawing the pawl.

4. A machine of the class described having in combination a gate beneath which a workpiece is presented, measuring rolls one of which is movable toward and from the other as the workpiece passes between them, a shoe adapted to be raised by the passage of a workpiece beneath it, a setting slide having rack teeth, hydraulic means responsive to movements of the movable measuring roll for moving the slide, a pawl device for engaging the ratchet teeth of the slide and preventing movement of said slide in a direction corresponding to increase in thickness of the workpiece as determined by the measuring rolls, a grading mechanism and means for adjusting said mechanism in accordance with the final position of the setting slide, means operated by raising of the shoe for moving the pawl device into operative relation with the rack teeth on the setting slide, means operated by the dropping of the gate off the trailing end of the workpiece for causing the pressure of the hydraulic means to be exerted upon the setting slide in a direction to hold the rack teeth firmly against the pawl device so that the setting slide is held firmly from movement, a member encountered and moved by the leading end of the workpiece, movement of which member causes the grading means to be adjusted in accordance with the position of the setting slide and the pawl device to be withdrawn from the ratchet teeth on the setting slide, and means operated by movement of the movable measuring roll just before the withdrawal of the pawl device, as the trailing end of the workpiece passes from between the measuring rolls, for reversing the direction of the hydraulic pressure.

5. In a machine for measuring the thickness of the thinnest spot in a selected locality of a workpiece and for operating in accordance with said thickness, a setting slide having rack teeth, a pawl device, yielding means constantly urging the pawl device towards the rack teeth, a rod one end of which is adapted to hold the pawl device out of engagement with the rack teeth, a spring tending constantly to move the rod away from the pawl device, a bar to which the rod is fast, an actuating pawl adapted to engage the bar and to hold the rod in position to hold the pawl device away from the ratchet teeth, means for disengaging the actuating pawl from the bar whereby the bar and rod permit the pawl device to engage the ratchet teeth on the setting slide whereupon the setting slide is permitted to move only in a direction corresponding to decrease in thickness of the workpiece as determined by the measuring rolls, and means becoming operative later to cause the actuating pawl to move the bar back to its first position and thereby move the pawl device away from the ratchet teeth on the setting slide.

6. In a machine for measuring the thickness of the thinnest spot in a selected locality of a workpiece and for operating in accordance with said thickness, a setting member, hydraulic means for adjusting the setting member, a plurality of pawls adapted to cooperate with the setting member to permit movement of the setting member in one direction but not in the other, means becoming operative at the end of the measuring operation for causing the hydraulic pressure to be exerted in a direction opposite to the direction of movement of the setting member permitted by the pawls whereby the setting member is held immovable for an interval, means for moving one of the pawls in a direction opposite to that exerted by the hydraulic pressure said movement

being idle or effective to move the setting member depending upon the adjusted position of said member, means becoming operative thereafter to reverse the direction of the hydraulic pressure, and means for withdrawing the pawls.

7. In a machine for measuring the thickness of the thinnest spot in a selected locality of a workpiece and operating in accordance with said thickness, a setting slide having on it a single row of rack teeth, a pawl device comprising two pawls adapted to engage the teeth and permit movement of the setting slide only in a direction corresponding to decrease in the thickness of the workpiece as measured by the measuring rolls, hydraulic means for moving the setting slide, means becoming operative when the trailing end of the workpiece leaves the measuring rolls for causing the hydraulic pressure to be exerted in a direction opposite to that permitted by the pawl device, and means for moving one of the pawls in a direction opposite to that exerted by the hydraulic pressure.

8. In a machine for measuring the thickness of the thinnest spot in a workpiece and for operating in accordance with said thickness, means for causing said operating means to operate with

respect to a workpiece, the thinnest spot of which does not measure an even multiple of the chosen unit of measurement, according to the multiple nearest said measurement, and, if said measurement is half way between one multiple and the next higher multiple of the chosen unit, then in accordance with the next higher multiple, said means comprising a setting slide the adjusted position of which determines the adjustment of the operating mechanism, said setting slide having a single row of ratchet teeth spaced apart a distance equal to a single chosen unit of measurement, hydraulic means for adjusting the setting slide, two pawls engaging the ratchet teeth both adapted to permit movement of the slide only in a direction corresponding to decrease in thickness of the workpiece as measured by the measuring rolls, the pawls being so constructed and arranged than when one pawl is engaging the effective face of one of the ratchet teeth on the setting slide, the other pawl is engaging a tooth half way between its effective face and its root, and means for causing one of the pawls to be moved to and fro lengthwise of the setting slide.
